(57) **CLAIM**

The ornamental design for rear lamp assembly for a motor scooter, as shown and described.

DESCRIPTION

FIG. 1 is a perspective view from the left side of a rear lamp assembly for a motor scooter.

FIG. 2 is a perspective view from the right side thereof.

FIG. 3 is a perspective view from the left side thereof.

FIG. 4 is a perspective view from the right side thereof.

FIG. 5 is a front elevation view thereof.

FIG. 6 is a rear elevation view thereof.

FIG. 7 is a left side elevation view thereof.

FIG. 8 is a right side elevation view thereof.

FIG. 9 is a top plan view thereof.

FIG. 10 is a bottom plan view thereof.

FIG. 11 is an enlarged right side view thereof.

FIG. 12 is an enlarged front view thereof; and,

FIG. 13 is an enlarged perspective view from the right side thereof.

The portion of the article shown in broken lines is for the purpose of showing environmental structure only and forms no part of the claimed design.
